(57) **CLAIM**

The ornamental design for an ultrasonic cutter, as shown and described.

DESCRIPTION

FIG. 1 is a top, front, right-side perspective view of an ultrasonic cutter, showing my new design;

FIG. 2 is a bottom, rear, left-side perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof; and,

FIG. 9 is an exploded top, front, right-side perspective view thereof, shown in reduced scale, shown in environmental use.

The broken lines in the drawings depict portions of the ultrasonic cutter that form no part of the claimed design. The additional broken lines showing a lid in FIG. 9 depict environmental subject matter forming no part of the claimed design.
